UNITED STATES PATENT OFFICE.

HARRY C. STOLZ, OF FRANKLIN, PENNSYLVANIA.

CYLINDER FOR GAS-ENGINES.

1,203,807.

Specification of Letters Patent.

Patented Nov. 7, 1916.

Application filed April 26, 1915. Serial No. 23,889.

To all whom it may concern:

Be it known that I, HARRY C. STOLZ, a citizen of the United States of America, and a resident of Franklin, Venango county, Pennsylvania, have invented certain new and useful Improvements in Cylinders for Gas-Engines, of which the following is a specification.

My invention relates to improvements in cylinders for gas engines of the valveless two-cycle type.

To start an engine of this type, as commonly constructed, it is necessary to turn the crank shaft, by hand power, (usually applied to the fly wheel), sufficiently to move the piston to the end of its compression stroke, in order to open the intake ports. With engines of even moderate size this requires the strength of more than one man.

The object of my invention is to so construct the cylinder and intake mechanism that an engine of this type may be started by a rocking movement of the crank shaft, 25 without a full compression stroke movement of the piston, and to do this in a better and more advantageous way than any heretofore devised.

I am aware that in the present state of the art, an engine of this type has been invented which may be started without a full compression movement of the piston, but heretofore, in certain engines, the auxiliary intake leading directly into the pump chamber has been constantly opened and at no time closed or otherwise controlled by the piston. Among the objections to such a construction is this, that with the auxiliary gas and air valves opened, as soon as the piston commences its backward movement, gas begins to flow into the pump chamber and continues to flow during the entire stroke of the piston.

I attain this object by the construction and mechanism illustrated in the accompanying drawing, in which:—

Figure 1, is a side elevation of a cylinder constructed in accordance with my invention; Fig. 2, a plan view of the supplementary intake pipes and valves; Fig. 3, a central longitudinal sectional elevation of the cylinder showing the piston in side elevation; Fig. 4, a partial side elevation of a cylinder, (partly in longitudinal section), as usually constructed, without my improvements, and Fig. 5, a partial side elevation,

partly in longitudinal section, of my improved cylinder.

Like reference characters indicate like parts throughout the several views.

Within the cylinder 1, the piston 2, is fitted to operate in the usual way. The front end of the cylinder 1, is extended beyond the cylinder proper to form the pump or mixing chamber 3, and is closed, preferably, by a head 4, having a stuffing box 5, through which the piston rod 6, is operated in the usual way. The regular air intake is through the opening and chamber 7, and the piston controlled port 18. The regular fuel intake may be through a separate port 8, so located as to be uncovered by the piston simultaneously with the port 18, when said piston reaches the end of its compression stroke, as shown in Fig. 4. As the piston 2, moves on the expansion stroke to the position in which it is shown in Fig. 3, it uncovers the exhaust port 11, and the bypass or transfer port 9, thus allowing the charge in the pump chamber 3, to blow through into the cylinder chamber 10.

In order that a charge, for starting, may be taken into the pump chamber before the piston reaches the end of the compression stroke, I provide a supplementary intake port 12 leading directly into said cylinder chamber and located nearer to the pump chamber than the regular intake port, so as to be uncovered by the piston 2, before said piston reaches the end of the compression stroke, or when in the position in which it is shown in Fig. 5. To complete the supplementary mechanism, an intake pipe 19, Fig. 2, is threaded into the outer portion of intake port 12, and is connected with the fuel supply by a pipe 14, controlled by a valve 17. An air pipe 13, is connected to the intake pipe 19, and is controlled by a valve 16. The valves 16 and 17, are operable by hand and are kept closed except when starting.

To start the engine, the piston is brought to the position as shown in Fig. 3, and valves 16 and 17, are opened and the crank shaft rocked forward until the piston is moved to the position shown in Fig. 5. This allows a charge, sufficient for starting, to be drawn into the pump chamber 3, through port 12. A reverse or backward movement of the crank shaft then operates the piston and thus closes the intake port 12, transfers the charge from chamber 3, to cylinder

chamber 10, compresses it until the piston again reaches the position as shown in Fig. 5, at which point the charge is fired, thus again reversing the movement of the crank 5 shaft and starting it forward.

In the mechanisms, hereinbefore referred to, the charge flows into the pump chamber during the entire backward movement of the piston, whereas, in mine, the supplementary intake port remains closed during nearly the entire backward movement of the piston, and the drop in pressure, or the partial vacuum, within the pump chamber is always the same, at the time this intake port 10 is opened, regardless of the piston speed. Although the drop in pressure within the pump chamber is not quite so great as when the regular intake, only, is used, it is only necessary to make the right adjustment of 15 the supplementary gas valve, in order to always obtain an explosive mixture, regardless of the piston speed. The right adjustment for the supplementary gas valve must, of course, be first found by trial, and 20 marked, and when set to that adjustment, the conditions for taking in the proper proportions of gas and air are practically the same as when the regular intake, only, is used, and no readjustment of the gas valve 25 is required.

It will be noted that, as the supplementary intake port 12, is piston controlled, no check valve is required in the intake pipe 19. It is thus apparent that with my mechanism, the variation of the throttle at the 30 time of starting is avoided entirely by the piston control of the supplementary intake port. No matter how slowly the piston moves, the intake port remains closed until 35 that movement of the piston opens it. Therefore, the vacuous condition in the piston chamber is always the same at the time the intake port is opened. Since, after once being determined and set, no further throt-

ting is necessary, and the explosive mixture 45 is practically uniform.

What I claim as my invention and desire to secure by Letters Patent is:—

In a gas engine of the valveless two-cycle type, a cylinder comprising a combustion chamber and a pump chamber constituting an extension of the combustion chamber and having a portion arranged coaxial with and being of larger diameter than the combustion chamber, inlet and exhaust ports for 50 the combustion chamber, a passage leading from the enlarged portion of the pump chamber to the inlet port, the walls of the enlarged portion of the pump chamber being otherwise solid and uninterrupted, a piston operable in the chambers, the pump chamber being provided in its wall with 55 separate and circumferentially alined air and gas intake ports over which the piston operates for closing and opening the same, 60 said piston on its compression stroke moving past the last mentioned ports to uncover the same and permit an influx of gas and air into the pump chamber, and a single combined air and gas intake port provided 65 in the pump chamber at a point between the enlargement of the latter and the first ports of said pump chamber and opened and closed by the piston so that when the piston uncovers said combined air and gas intake 70 port a uniform vacuous condition will exist in the pump chamber to permit of a uniform quantity of the combustible mixture being drawn in on the initial strokes, which are imparted by an exterior agency, in 75 effecting a starting of the engine.

Signed at Zanesville Ohio this 21 day of April 1915.

HARRY C. STOLZ.
